UNITED STATES PATENT OFFICE.

EDWARD W. GERRISH, OF LYNN, MASSACHUSETTS.

LAST.

1,007,092.

Specification of Letters Patent. Patented Oct. 31, 1911.

Application filed April 26, 1911. Serial No. 623,743.

To all whom it may concern:

Be it known that I, EDWARD W. GERRISH, a citizen of the United States of America, and a resident of Lynn, in the county of Essex and State of Massachusetts, have invented certain new and useful Improvements in Lasts, of which the following is a specification.

This invention relates to lasts, particularly to divided lasts connected together by a hinge, and having a portion of the hinge cut away to permit the shortening of the last when the heel part is moved about the hinge pivot toward the fore part.

The particular object of the invention is to provide a simple hinge of great strength which may be manufactured very cheaply, and it consists in positioning within a transverse opening in the fore part a cylindrical member having a diametrical threaded opening therein, in which is positioned the threaded end of a bolt mounted in the heel part and extending through a vertical slot communicating with the said transverse opening.

The invention further consists of a locking bolt adapted when the last is lengthened to extend through an opening in the fore part and into a recess in said cylindrical member.

The invention further consists in a spring pressed tubular plug mounted in a recess in the fore part with its outer closed end rounded and bearing against the front face of the heel part.

The invention further consists in providing the fore part with a projection in which the hinge plug is mounted, having a face slightly eccentric to the center of said plug, so that when the last is shortened by moving the heel part about the hinge pivot, the contacting face of said heel part will bind on said eccentric face and retain it in such adjusted position.

The invention further consists in certain novel features of construction and arrangement of parts which will be readily understood by referring to the description of the drawings and to the claims hereinafter given.

Of the drawings: Figure 1 represents a longitudinal vertical section of a last embodying the features of the present invention, Fig. 2 represents a similar view of the same, showing the heel part moved into position to shorten the last, Fig. 3 represents a

horizontal sectional detail, the cutting plane being on line 3-3 on Fig. 1, Fig. 4 represents a horizontal section of a portion of the last, the cutting plane being on line 4-4 on Fig. 1, and Fig. 5 represents a diagrammatical view showing the eccentricity of the projection on the fore part, in which the hinge plug is positioned.

Similar characters designate like parts throughout the several figures of the drawings.

In the drawings, 10 and 11 represent respectively a fore part and a heel part of a last, the upper opposing faces of which are separated as indicated at 12. From the rear face of the fore part 10 is a projection 13, through which extends a cylindrical transverse opening 14, in which is centrally positioned a cylindrical metal plug 15 of less length than the opening 14. This plug 15 is revoluble within said opening 14, and when positioned therein the ends of the opening 14 are closed by wooden plugs 16 glued therein and having their ends formed to conform to the shape of the last. The projection 13 has a curved face 17 slightly eccentric to the axis of the opening 14, one portion thereof intermediate its ends extending slightly beyond the end portions thereof, as clearly indicated in diagram in Fig. 5 of the drawings. This projection 13 fits into a concaved recess formed in the front face of the heel part 11, as indicated in Figs. 1 and 2 of the drawings. The projection 13, with its eccentric curved face 17 on the fore part 10, and the concaved recess of the heel part 11, in which said projection is positioned, are formed when the last is being sawed to divide it.

The outer portion of the projection 13 is provided with a vertical slot 18 communicating with the transverse opening 14. The heel part 11 has bored therein, longitudinally thereof, a cylindrical hole 19, communicating with a larger cylindrical hole 20 in alignment therewith, the inner end of the hole 20 forming a shoulder 21. Positioned within the opening 19 is a bolt 22, the threaded end of which projects beyond the front face of the heel part 11, through the vertical slot 18, and is threaded to a diametrical threaded opening 23 in the plug 15. The head 24 of the bolt 22 bears against the shoulder 21, and by turning the bolt 22 the fore part 10 and heel part 11 may be adjusted relative to each other to produce the required amount.

110

of friction between the contacting surfaces of the projection 13 and the recess of the heel part in which said projection is mounted. Owing to the eccentricity of the face 17 of said projection 13, it is obvious that when the heel part is moved about the center of the plug 15, a more rigid binding effect is produced which is sufficient to retain the heel part in adjusted position when the last 5 is shortened. When the bolt 22 is adjusted properly, means are provided to prevent the accidental displacement or rotation of the bolt 22 by inserting into the larger hole 20 a loose plug 25 against the outer end of 15 which is inserted an outer plug 26, which is glued in position and has its outer end finished to conform to the shape of the last. By this construction of a hinge a very 20 rigid connection is made between the fore 25 part and the heel part of the last, which has great strength, and is wholly inclosed so that its parts cannot, under any circumstances, become displaced.

Should contacting surfaces become worn 25 to any extent so that the frictional contact between the two parts of the last is insufficient for the proper operation thereof, the plug 26 may be bored out, the loose plug 25 removed, and the bolt 22 adjusted to renew the frictional contact. After this has been accomplished, the loose plug 25 is returned into the opening 20 and a new plug 26 is inserted and secured in position. In a 30 vertical hole in the front end of the heel part 35 11 is mounted a locking bolt 27, the lower end of which normally extends through an opening 28 in the projection 13, with its extreme end positioned within a peripheral recess 29 formed in the plug 15. The upper 40 end of the bolt 27 is surrounded by a staple 30, between which and a shoulder on said bolt 27 is interposed a spring 31, normally retaining the bolt 27 in the position indicated in Fig. 1 of the drawings. The upper 45 end of the bolt 27 is provided with a thumb piece 32 by which the bolt 27 may be withdrawn from the recess 29 and from the hole 28 to permit the movement of the heel part 11 about the pivot of the hinge when it is 50 desired to shorten the last. During this shortening operation the end of the bolt 27 rides along the curved face 17 of the projection 13, as indicated in Fig. 2 of the drawings. When the heel part 11 is returned to 55 its normal position, as indicated in Fig. 1, the spring 31 will operate to cause the bolt 27 to again enter the hole 28 and the recess 29, and the two parts 10 and 11 will again be locked in position. This return movement of the heel part 11 to its normal position is assisted by the hollow spring pressed 60 plug 33, the outer end of which is rounded to press against the front face of the heel part 11, while its opposite open end is inserted in the hole or recess 34 formed in the 65

fore part 10. A spring 35 is mounted in the hollow plug 33 and the hole 34, and as soon as the heel part 11 has been moved sufficiently far to pass the eccentric portion of the projection 13, the operation of the spring 35 will complete the movement of the heel part 11 about the hinge pivot until it has reached its normal position. This makes a very effective last which is simple in its construction, and has its operating parts all 70 entirely inclosed and protected from any foreign substances which might interfere with their operation.

It is believed that the operation and many advantages of the invention will be thoroughly understood without any further description.

Having thus described my invention, I claim:

1. A last consisting of a fore part and a 85 heel part; a transverse member positioned in the fore part and adapted to oscillate therein; a bolt in the heel part extending through a vertical slot in the fore part and threaded to said transverse member.

2. A last consisting of a fore part and a heel part; a transverse member positioned in the fore part and adapted to oscillate therein; a bolt in the heel part extending through a vertical slot in the fore part and 90 threaded to said transverse member; and means preventing the turning of said bolt.

3. A last consisting of a fore part having a transverse cylindrical opening therethrough and a vertical slot communicating therewith; a cylindrical member positioned in said opening and having a diametrical threaded hole therein; a heel part having a longitudinal hole therein; and a bolt in the longitudinal hole in said heel part with its 100 threaded end extending therefrom through said vertical slot into the threaded hole of 105 said cylindrical member.

4. A last consisting of a fore part having a transverse cylindrical opening therethrough and a vertical slot communicating 110 therewith; a cylindrical member positioned in said opening and having a diametrical threaded hole therein; a heel part having a longitudinal hole therein; a bolt in the longitudinal hole in said heel part with its 115 threaded end extending therefrom through said vertical slot into the threaded hole of said cylindrical member; and plugs for closing the ends of said transverse opening.

5. A last consisting of a fore part and a heel part; a cylindrical transverse member positioned in the fore part and adapted to oscillate therein; a member extending from the heel part through a vertical slot in the 125 fore part and secured to said transverse member.

6. A last consisting of a fore part and a heel part; a cylindrical transverse member positioned in the fore part and adapted to 130

oscillate therein; a member extending from the heel part through a vertical slot in the fore part and secured to and adjustable longitudinally in said transverse member.

5 7. A last consisting of a fore part and a heel part; a cylindrical transverse member positioned in the fore part and adapted to oscillate therein; a bolt in the fore part and threaded to said transverse member; and a

member secured in the heel part and bearing against the end of said bolt to prevent its rotation. 10

Signed by me at 4 Post Office Sq., Boston, Mass., this 25th day of March, 1911.

EDWARD W. GERRISH.
